(57) CLAIM

The ornamental design for a drawer, as shown and described.

DESCRIPTION

FIG. 1 is a perspective view of a drawer, showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view thereof;

FIG. 9 is an enlarged view of portion 9 shown in FIG. 1;

FIG. 10 is an enlarged view of portion 10 shown in FIG. 3;

FIG. 11 is an enlarged view of portion 11 shown in FIG. 4;

FIG. 12 is an enlarged view of portion 12 shown in FIG. 7; and,

FIG. 13 is an enlarged view of portion 13 shown in FIG. 8.

The dot-dash broken lines depict the boundaries of the enlargements that form no part of the claimed design.

1 Claim, 13 Drawing Sheets
